FUSE PLUG

Filed April 25, 1930

THOMAS B. BURNO 34

By Thomas R. Harvey Attorney

UNITED STATES PATENT OFFICE

THOMAS B. BURNO, OF WASHINGTON, DISTRICT OF COLUMBIA

FUSE PLUG

Application filed April 25, 1930. Serial No. 447,393.

My present invention relates to improvements in fuse plugs for electrical circuits, as for electric lamps, and especially to an emergency signal for indicating the burning out 5 of a fuse in the fuse plug. The fuse plugs of my invention are adapted for use in the usual fuse sockets in cut-out or fuse-plug boxes, ordinarily found upon the basement wall of a house, or other building that is 10 wired for electric lighting.

As is well known, when a fuse blows out and the lamps of a circuit are extinguished, the ordinary householder has difficulty in ascertaining which one of several fuse plugs in 15 the cut-out box has burned its fuse.

In carrying out my invention I substitute for the usual fuse plugs a set of plugs involving my invention, and each of the improved plugs includes an incandescent lamp or signal, which lamp is normally extinguished. When the fuse of any one of the plugs burns out from any cause, the lamp of the burned out plug is automatically illuminated, thus indicating to the observer which plug requires 25 a fresh fuse.

The plugs are equipped with means for replacing and renewing the fuses, and such fuses or fuse-links may with facility and convenience be substituted for the burned fuse-links.

The invention consists in certain novel combinations and arrangements of parts as will hereinafter be more fully set forth and claimed.

In the accompanying drawings I have illustrated one complete example of the physical embodiment of my invention wherein the parts are combined and arranged according to one mode I have thus far devised for the 40 practical application of the principles of my invention, but it will be understood that changes and alterations may be made in the exemplified structure within the scope of my claims without departing from the principles 45 of my invention.

Figure 1 is a view of a signaling fuse plug embodying my invention, part of the covering being shown in section. Figure 2 is a view from the opposite side of Figure 1, with the 50 lamp bulb omitted.

Figure 3 is an enlarged detail sectional view through the body of the plug, omitting the lamp, and showing the removable fuse member in elevation.

Figure 4 is a detail sectional view of the 55 fuse member removed from the body of the plug.

Figure 5 is a section at line 5—5 of Figure 4.

In carrying out my invention I employ a 60 standard, small size incandescent lamp 1 having the usual screw head 2 which threads into the complementary shell 3 of the body of the plug. The body of the plug, as here shown comprises three sections 4, 5, and 6, of 65 suitable material such as porcelain, and these sections are recessed, grooved, and slotted as usual for the accommodation of the conductors and other electrical elements of the fuse plug.

The sections are fastened together by means of bolts or screws 7 and 8, and clamped with nuts 9 on the threaded ends of the screws as indicated in the drawings.

The plug is fashioned with a threaded head 75 10 that screws into the usual socket provided to receive the fuse plug.

In the preferred form of my invention I utilize a removable fuse holder which includes a post 11 of suitable insulating material that is fashioned with a pair of diametrically arranged wings 12, and a contact head 13 is carried at one end of the post for contact with a complementary contact member in the socket to which the fuse plug is attached. This contact head is formed integral with a tubular stem 14 that is rigidly carried in the post, and a slide bolt 15 is enclosed in the stem and is fashioned with a contact head 16 at the end of the holder opposite to the head 13.

Within the tubular stem, and interposed between the head 13 and the inner end of the slide bolt, I locate a spring 17 that has a tendency to urge the headed bolt from the tubular stem.

The holder-post 11 has secured thereto an inset, fixed metallic ring 18 having a tapered annular flange 18', and this flange 18' is employed in holding the fuse link 19. The fuse link is a thin strip of suitable material 100

that is weakened by cutting out its edges as 19', and the link is readily burned out and severed when the load becomes sufficiently heavy, as to "blow" the fuse.

5 The fuse link is retained on the holder, at one end, by a clamp ring 20 having a pair of clamp flanges 20a, one of which flanges contacts with the tapered flange 18' of the fixed ring 18. At its other end the fuse link is 10 retained by a cap 21 fitted over the head 16 of the slide bolt 15. In applying the fuse link, the holder is first removed from the plug, the cap 21 is removed from the head 16 and the clamp ring 20 is loosened around the fixed 15 ring 18. One end of the link is then clamped between the tapered rings 18 and 20. The slide bolt is then retracted or pushed within its stem against the tension of the spring, the end of the link is laid against the side 20 of the head and the cap is then fitted over the end of the link and the head. Both ends of the link are held frictionally by the clamping members, to withstand the tension of the compressed spring 17, and the spring and link 25 hold the slide bolt in its retracted position in the tubular stem. If and when the fuse is severed, as by a "blow", the spring is free to project the slide bolt and its head closes a lamp circuit as will be described.

30 The detachable clamp ring 20 is slotted at 22 to accommodate the wings 12 of the holder, and these wings hold the ring against turning and guide it as it is slid into or out of engagement with one end of the fuse link.

35 The holder is inserted in the hollow body section 6 of the plug, the two wings frictionally engaging in grooves within the section, and a resilient leaf 23 rigid with or integral with the shell 10 occupies one of these grooves 40 for frictional engagement with the holder, so that the latter is frictionally retained within the hollow section, with the contact head 13 exterior of the plug.

Within the hollow section 6 a stationary 45 contact head 24 is located, against which the capped head 16 impinges when the fuse link is severed and the spring 17 projects the slide bolt and contact head.

50 Before the fuse link is severed, or burned out, the current from the plug socket (not shown) passes through the head 13, stem 14, and head 16 to the link 19, thence by way of rings 18 and 20 to the shell 10 of the plug and to the shell of the socket in the head shell 55 10 is screwed, and from there the usual connections or wiring is made to the source of electrical supply.

When the capped head 16 frictionally engages the stationary head 24, the lamp 1 is 60 illuminated, thus giving a warning or signal that the plug of lamp 1 is the fuse plug that has "burned out", in order that a fresh fuse link may be applied to the holder after the severed ends have been removed.

65 To the stationary head 24 a wire 25 is at-

tached and this wire is passed through an opening in the section 5 and welded or connected to a terminal plate 26 that is secured by a terminal screw 27 to the body of the plug.

This plate is provided with a resilient or spring blade 28 that forms part of the usual lamp switch, of which the key is indicated as 29 and the pivot pin is 30. The pin extends transversely through the body of the plug and near one end is fashioned with a cam head or connector 31 that is designed, when the key is turned to frictionally engage the blade 28 and a complementary blade 32 of the switch. In Figure 3 the lamp switch is shown turned to open position, but it will 80 be understood that the switch is closed in order that the lamp may automatically be illuminated when the fuse link is severed.

The spring blade 32 is of U-shape and is secured in the end of the hollow section 4 by means of a stud 33, which stud also secures the usual contact head 34 to the section and is adapted for frictional and electrical connection with the lamp contact-member on the shell head 2 of the lamp.

The return current from the lamp passes through its shell 2 to the socket shell 3, and thence through a plate 35, and wire 36 to the point 37 where the wire is soldered to the shell 10 of the plug.

The screw or bolt 7, which aids in securing together the three body sections, is employed to secure the bent end of the plate 35 at the end of the section 4, and a screw 38 also secures the plate 35 at the side of the device.

When the fuse link is burned out or severed, the lamp circuit controlled by this plug device is cut off from the main line wires, and the signal lamp 1 only, is illuminated at the fuse plug. The current for the signal lamp passes from the main line through head 13 and thence through the connections along the central interior of the plug device to the lamp, thence out through the shell 3, plate 35, wire 36 and point 37 to the shell 10 and from there through the shell of the socket into which plug 10 is screwed to the negative wire of the main line.

Various changes may be made in the exemplified structure, and the usual necessary accessories, such as a cover or shield 39, are contemplated in the construction of the fuse device for giving the proper finish to the device, and of course one of these fuse plugs is used at the fuse board for controlling each lighting circuit in a dwelling, or other place to be lighted.

From the above description taken in connection with my drawings, it will be apparent that the lamp 1 is illuminated as a visible signal to indicate the location of a burned out fuse in a lamp circuit, and the defective plug may readily be replaced by a new one.

Having thus fully described my inven-

tion, what I claim as new and desire to secure by Letters Patent is:—

- 6 1. The combination in a fuse plug having an electric lamp and a normally open lamp circuit, a normally closed circuit for the plug including a fuse-link, said plug circuit including a movable contact member operable when the link is severed for closing the lamp circuit when the plug circuit is broken.
- 10 2. The combination in a sectional fuse plug having an electrically operated signal lamp mounted in one section, a stationary contact head for the signal lamp mounted in another section, and electrical connections between said head and the lamp mounted in an intermediate section, of a fuse holder mounted in the second mentioned section, a fuse link, stationary means on the holder for retaining one end of the link and movable means on the holder for retaining the other end of the link, and means for moving the latter means to contact with said head when the link is severed.
- 15
- 20

In testimony whereof I have affixed my
25 signature.

THOMAS B. BURNO.
